UNITED STATES PATENT OFFICE.

WILLIAM D. WATSON AND JOHN A. KNISELY, OF CHICAGO, ILLINOIS.

WINDOW.

SPECIFICATION forming part of Letters Patent No. 665,290, dated January 1, 1901.

Application filed October 1, 1900. Serial No. 31,631. (No model.)

To all whom it may concern:

Be it known that we, WILLIAM D. WATSON and JOHN A. KNISELY, citizens of the United States, residing at Chicago, in the county of Cook, in the State of Illinois, have invented certain new and useful Improvements in Windows, of which the following is a specification.

Our invention relates to improvements in swinging windows, and more particularly to windows of sheet-metal construction—such, for example, as that set forth in the prior patent, No. 652,553, granted to William D. Watson June 26, 1900. It is well known to those skilled in this art that however nicely the frames and casings of such windows may be constructed and however carefully fitted to each other when first put in place the almost inevitable settling of the building will in many cases cause the windows to bind and stick, so that they can be operated only with great difficulty unless thoroughly overhauled and readjusted at a considerable expense, and it frequently happens that such overhauling and readjustment are repeatedly required during the life of the structure.

A principal object of the present invention is to provide means whereby the window-sash may be adjusted within their frames sufficiently to compensate for any ordinary racking or distortion of the casing brought about by the settling of the building or otherwise; and to this end the invention consists in the matters herein set forth, and particularly pointed out in the appended claims, as will be fully understood from the following description of the construction illustrated in the accompanying drawings, in which—

Figure 1 is a transverse sectional elevation of a window sash and casing made relatively adjustable in accordance with our invention, the section being taken on line 1 1 of Fig. 5. Fig. 2 is a transverse sectional elevation taken on line 2 2 of Fig. 1. Fig. 3 is a sectional elevation taken on line 3 3 of Fig. 5. Fig. 4 is an enlarged sectional detail taken on the same plane as Fig. 1. Fig. 5 is a horizontal sectional detail taken on the plane of line 5 5 of Fig. 1. Fig. 6 is a perspective detail of the adjustable pivot with its parts separated.

In said drawings, 1 designates the window-sash, within which the glass G is secured in any suitable manner, and 2 is the window-

casing, which is built into the aperture provided in the wall of the building to receive it. The sash-frame is herein shown as of tubular construction, with an inwardly-projecting channel 4 extending entirely around the frame and forming a condensation-gutter, at the bottom of which one or more apertures 5 are desirably provided to permit the escape of any moisture collected therein. The pivot bolts or screws 6, which support the sash, are herein shown as passing through this channel portion 4 and through the adjacent sides of the window-casing and are so located that the weight of the sash always tends to swing it closed. A suitable chain or other contrivance (not herein illustrated) may then be provided for holding the sash open when desired.

To permit the sash to be adjusted within the casing, the pivots 6 are adjustably secured with reference thereto. This is accomplished in the approved construction shown by passing the pivot through a close-fitting aperture 7 in an adjustable block 8, as better shown in Figs. 4 and 6. This block 8 is provided with slots 9, through which clamping-screws 10 may be passed into threaded apertures 11 in the wall of the sash-frame or in a reinforcing-plate 12, which is rigidly secured to the sash by rivets 13. The pivot 6 projects from the plate 9 inwardly through an elongated slot 14, cut through the sash and its reinforcing-plate 12, and enters a threaded aperture 15, which is suitably located in the adjacent wall of the window-casing, and which, as herein shown, extends also through a reinforcing-plate 16, secured to the inner face of said casing by rivets 17. The utility of the adjustment thus provided will be better understood from a consideration of Fig. 1, in which the casing 2 is assumed to be racked out of shape by the settling of the building or otherwise. This tends to cause the sides of the sash to bind on the casing at opposite upper and lower corners, as at 18; but such tendency may be practically overcome to an extent sufficient to permit the sash to still swing freely by loosening the clamping-screws 10 and adjusting the sash on its pivot so as to raise it on one side and lower it on the other, the clamping-screws being tightened again as soon as the bind is

released. This adjustment will obviously not interfere with the tight closing of the sash along its top and bottom edges against the outer and inner stops 19 and 20, respectively. 5 At the sides of the window, however, the strips or other devices provided for excluding the weather should be of such a nature as to automatically compensate for any angularity resulting between the sides of the sash and casing. To this end the window is shown as provided, in accordance with the said prior patent, No. 652,553, with spring - pressed weather-bars 21, seated in vertical grooves or recesses 22 in the sides of the casing 2. These bars project, when the sash is closed, into vertical grooves 23, formed in the adjacent side surfaces of the sash, and fit therein so closely as to effectually keep out both wind and moisture. When the sash is swung on its pivots 20 6, the weather-bars are forced back into the recesses 22 by the wedging action of the sash on the curved surfaces of the bars; but when the sash is returned to its closed position the bars instantly swing forward again into the 25 grooves and seal the openings between the sides of the sash and casing regardless of the varying width of the crack caused by the irregular adjustment between them. (See Fig. 3.) 30 As herein shown, the weather-bar springs 24 are bow-shaped plate-springs that are removably secured to the tubes by screws 25; but obviously they may be otherwise formed or provided as desired. It will also be un-

derstood that various other changes may be 35 made in the details of the construction described without involving any material departure from the broad invention claimed.

We claim as our invention—

1. The combination with a window-casing, 40 of an inclosed sash adjustably pivoted within the casing, substantially as described.

2. The combination with a window-casing and inclosed sash, of pivots passing between the casing and sash, and means for adjusting 45 said pivots relatively to the sash, substantially as described.

3. The combination with a window-casing and inclosed sash, of pivots mounted in plates adjustably secured to the sash and extending 50 through slots in the sash into the casing, substantially as described.

4. The combination with a window-casing, of an inclosed sash adjustably pivoted within the casing, and weather - bars yieldingly 55 mounted between the pivot sides of the casing and sash to close the crevice between them whatever their angular adjustment, substantially as described.

In testimony that we claim the foregoing as 60 our invention we affix our signatures, in presence of two subscribing witnesses, this 25th day of September, A. D. 1900.

W. D. WATSON.
JOHN A. KNISELY.
